UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SIGNATURE-HANDLING MACHINE.

1,264,753.

Specification of Letters Patent. Patented Apr. 30, 1918.

Application filed February 26, 1915. Serial No. 10,755.

To all whom it may concern:

Be it known that I, HOWARD M. BARBER, a citizen of the United States, and resident of Stonington, in the county of New London and State of Connecticut, have invented a new and useful Improvement in Signature-Handling Machines, of which the following is a specification.

This invention includes means whereby successive signatures are led through different stitcher and folding mechanisms to a common delivery point. This invention more specifically includes means whereby the signatures are alternately fed to two stitcher and two folding mechanisms and are fed from the folding mechanisms to a common delivery mechanism.

This invention also more specifically includes a common delivery cylinder having grippers arranged to take the stitched and folded signatures from the jaws of their respective female folding cylinders.

The object of this invention is to provide means for rapidly stitching, folding and delivering signatures and, at the same time, permit the stoppage of the signatures an ample time to allow them to be accurately stitched.

A practical embodiment of my invention is represented in the accompanying drawings, in which —

Figure 1 is a vertical central section taken from front to rear through so much of a sheet handling machine as includes my invention.

Fig. 2 is a detail vertical section taken from front to rear inside the near side frame,

Fig. 3 is a similar section taken inside the far side frame, and

Fig. 4 is a detail section showing the driving connection between the parts and also certain of the cam mechanisms.

A feeding cylinder 1 is mounted on a shaft 2 and carries two sets of grippers 3, 4, arranged to take successive signatures as they are fed through the guides 5, 6, and feed the signatures alternately to the cylinders 7, 8, of the feeding-in devices for the stitcher mechanisms.

The shaft of the cylinder 7 is denoted by 9 and the shaft of the cylinder 8 by 10. The set of grippers 11 on the cylinder 7 is arranged to take a signature from the

set of grippers 3 every revolution of the cylinder 1 and every two revolutions of the cylinder 7. The set of grippers 12 on the cylinder 8 is arranged to take a signature from the set of grippers 4 on the cylinder 1 every revolution of the cylinder 1 and every second revolution of the cylinder 8.

The upper stitcher table is denoted by 13 and the lower stitcher table by 14.

A movable stop 15 is provided for the table 13 and a movable stop 16 is provided for the table 14.

The upper stitcher mechanism is denoted by 17 and the lower stitcher mechanism by 18, which stitcher mechanisms are driven respectively through suitable gearing from the shafts 19 and 20.

Endless tape carriers 21, 22, are arranged to feed the signatures from the cylinder 7 onto the stitcher table 13 against the movable stop 15. Similarly, endless tape carriers 23, 24, are arranged to feed the signatures from the cylinder 8 onto the stitcher table 14 against the movable stop 16.

The upper male folding cylinder is denoted by 25, its shaft by 26, its set of grippers by 27 and its tucking blade by 28. The lower male folding cylinder is denoted by 29, its shaft by 30, its set of grippers by 31, and its tucking blade by 32. The upper female folding cylinder is denoted by 33, its shaft by 34, and its folding jaws by 35. The lower female folding cylinder is denoted by 36, its shaft by 37 and its set of folding grippers by 38.

The common delivery cylinder is denoted by 39, its shaft by 40 and its two sets of grippers by 41, 42, the grippers 41 serving to take the stitched and folded signatures from the grippers 35 of the upper female folding cylinder and the grippers 42 serving to take the stitched and folded signatures from the grippers 38 of the lower female folding cylinder. These grippers 41, 42, are arranged to deliver the sheets to a suitable delivery device, such, for instance, as an endless carrier 43.

The short circular cam 44 is arranged to operate the grippers 3 of the cylinder 1 to close them on the signature at their receiving point and to open them at the proper time to release the signature to the grippers 11 of the cylinder 7. The long circular cam 45 is arranged to operate the grippers 4 of

the cylinder 1 to close them on the next succeeding signature at their receiving point and to open them to release the signature to the grippers 12 of the cylinder 8. The 5 cam 46 controls the operation of the grippers 11 and the cam 47 controls the operation of the grippers 12.

As the near side frame has been omitted in the drawings, for the sake of clearness the 10 connections of the support for these cams 44, 45, 46 and 47 are not shown, it being understood that these supports for the cams may be connected to the frame in any well known or approved manner.

15 The movement of the sheet stop 15 is controlled by the rotary cam 48 carried by the cylinder 25 and the movement of the sheet stop 16 is controlled by the rotary cam 49 carried by the cylinder 29.

20 The grippers 27 on the cylinder 25 are shown as tumbler-operated and they are controlled at their receiving point by the pin 50 and at their releasing point by the pin 51. Similarly, the grippers 31 on the cylinder 29 are shown as tumbler-operated and they are controlled at their receiving point by the pin 52 and at their releasing point by the pin 53.

30 The coacting folding mechanisms of the male and female folding cylinders 25, 33, and 29, 36, are of the floating tucking blade and floating folding jaw type of well known and approved form and their operating cam mechanisms will not be specifically described 35 herein as they form no part of the present invention. See United States Letters Patent to R. C. Seymour, No. 629,928, August 1, 1899.

40 The grippers 41 and 42 are operated by the cams 54, 55, to receive the folded and stitched signatures from their respective female folding cylinders and deliver the said signatures onto the delivery device 43.

A stripper guide may be interposed between the cylinder 39 and delivery device 43.

45 The driving shafts 19 and 20 of the stitcher mechanisms are driven from the shaft 2 of the cylinder 1 through the train of gears 56, 57, 58, 59, the gears 60, 61, on the shafts 9, 50 10, meshing with a gear 62 on the shaft 2.

The cylinders 29, 36, 39, 33, and 25, are driven from the gear 61 through the gears 63, 64, 65, 66, 67, 68. In the present instance, these cylinders are all driven at the 55 same surface speed as the cylinder 1.

By sending one signature to one stitcher mechanism and the next signature to another stitcher mechanism, I am enabled to stitch one signature while the other one is being 60 fed into position for stitching. This alternate stitching of the signatures permits first one stitched signature to be folded and delivered to the delivery device and then the other stitched signature to be folded and delivered to the delivery device.

It will thus be seen that ample time is given for the stitching and delivery of the successive signatures.

By the term "cylinder" as used in the description, I contemplate any suitable means 70 for passing the signatures through the prescribed paths and by the term "grippers" I contemplate any engaging devices suitable for the purpose of leading the signatures through said prescribed paths. 75

It is evident that slight changes might be resorted to in the form, construction and arrangement of the several parts without departing from the spirit and scope of my invention; hence I do not wish to limit myself 80 strictly to the structure herein set forth, but What I claim is:—

1. In a machine of the character described, a plurality of stitcher mechanisms, a plurality of folding mechanisms, a common delivery mechanism, and means for passing successive signatures through their respective stitching and folding mechanisms to the common delivery mechanism. 85

2. In a machine of the character described, two stitcher mechanisms, two folding mechanisms, a common delivery mechanism and means for passing successive signatures in different paths through their respective stitching and folding mechanisms to the common delivery mechanism. 90

3. In a machine of the character described, a common source of signature supply, a plurality of stitcher mechanisms, a plurality of folding mechanisms, a common delivery mechanism, and means for passing successive signatures from the common source of signature supply through their respective stitching and folding mechanisms to the common delivery mechanism. 100

4. In a machine of the character described, a common source of signature supply, two stitcher mechanisms, two folding mechanisms, a common delivery mechanism, and means for passing successive signatures from the common source of signature supply in different paths through their respective stitching and folding mechanisms to the common delivery mechanism. 110

5. In a machine of the character described, a plurality of stitcher mechanisms, means for feeding signatures thereto, a plurality of female folding cylinders, a plurality of male folding cylinders arranged to remove the stitched signatures and fold them off to the female folding cylinders and a common delivery cylinder arranged to take the stitched and folded signatures from said female folding cylinders. 115

6. In a machine of the character described, two stitcher mechanisms, means for feeding signatures thereto, two female folding cylinders, two male folding cylinders arranged to take the stitched signatures from the stitcher mechanisms and fold them 125 130

off to the female folding cylinders and a common delivery cylinder arranged to take the stitched and folded signatures from said female folding cylinders.

5 7. In a machine of the character described, a plurality of stitcher mechanisms, means for feeding signatures thereto, a plurality of female folding cylinders having folding jaws, a plurality of male folding cylinders having grippers for positively removing the stitched signatures from the stitcher mechanisms and also having folding blades arranged to coact with the folding jaws of the female folding cylinders for 10 folding off the stitched signatures and a common delivery cylinder having two sets of grippers for removing the stitched and folded signatures from their respective female folding cylinders.

15 8. In a machine of the character described, two stitcher mechanisms, means for

feeding signatures thereto, two female folding cylinders having folding jaws, two male folding cylinders having grippers for positively removing the stitched signatures from the stitcher mechanisms and also having folding blades arranged to coact with the folding jaws of the female folding cylinders for 25 folding off the stitched signatures, and a common delivery cylinder having two sets of grippers for removing the stitched and folded signatures from their respective female folding cylinders.

In testimony that I claim the foregoing as my invention, I have signed my name, in 30 presence of two witnesses, this twenty fourth day of February, A. D. 1915.

HOWARD M. BARBER.
